(57) **CLAIM**

The ornamental design for a segment tote bag, as shown and described.

DESCRIPTION

FIG. 1 is a front perspective view of a segment tote bag, showing my new design;

FIG. 2 is a front elevation view thereof;

FIG. 3 is a rear elevation view thereof;

FIG. 4 is a left side elevation view thereof, the right side being an identical image thereof;

FIG. 5 is a top plan view thereof; and,

FIG. 6 is a bottom plan view thereof.

The evenly spaced dashed broken lines in FIGS. 1-6 depict seams and form no part of the claimed design. The broken lines in FIG. 6 depict studs and form no part of the claimed design.
